United States Patent Office

Des. 230,226
Patented Feb. 5, 1974

230,226

LOUNGE

Henry Olko, Applegreen Drive,
Old Westbury, N.Y. 15568

Filed Jan. 11, 1972, Ser. No. 217,076

Term of patent 14 years

Int. Cl. D6—01

U.S. Cl. D6—38

Fig. 1

Fig. 2

Fig. 3

FIG. 1 is a perspective view of a lounge embodying my design.

FIG. 2 is a side view of the lounge of FIG. 1.

FIG. 3 is a top view of the lounge of FIG. 1.

The side of the lounge seat not shown is a mirror image of the side shown.

I claim:

The ornamental design for the lounge, as shown and described.
